(57) CLAIM

The ornamental design for handle, as shown and described.

DESCRIPTION

FIG. 1 is a front view of a first embodiment of our new design of a handle; a rear view, a top view and a bottom view thereof being the same as the front view;

FIG. 2 is a left side view of the first embodiment of our new design of the handle;

FIG. 3 is a right side view of the first embodiment of our new design of the handle; and,

FIG. 4 is a perspective view of the first embodiment of our new design of the handle.
